DESIGN FOR A BADGE

Ralph O. Yardley, Stockton, Calif., assignor to
The Association of 20-30 Clubs, Sacramento,
Calif., a corporation of California

Application January 4, 1937, Serial No. 66,889

Term of patent 14 years

To all whom it may concern:

Be it known that I, Ralph O. Yardley, a citizen of the United States and a resident of Stockton, county of San Joaquin, State of California, have invented a new, original, and ornamental Design for a Badge, of which the following is a specification, reference being had to the accompanying drawing forming part thereof.

Fig. 1 is a plan view of a badge, showing my new design; and

Fig. 2 is an edge view thereof.

I claim:

The ornamental design for a badge, as shown.

RALPH O. YARDLEY.
